WALTER A. HEINRICH, OF ST. LOUIS, MISSOURI

EARTH ANCHOR

Application filed February 2, 1931. Serial No. 512,932.

This invention relates to improvements in earth anchors and more particularly to anchors of the helical or screw type capable of insertion in soils of the usual type by a rotary movement imparted to an associated torsion member.

A difficulty is experienced in screw anchors of prevailing types in that a special wrench, or at least a pipe-wrench, is required for driving the anchor. After the anchor is once embedded in the earth to the desired depth, the reinsertion of such wrench or other driving means is, of course, impossible without excavating to the depth of the anchor. Further, the necessity of carrying special tools for driving anchors of this type is inconvenient and uneconomical. The inability to recover, without expensive excavation, an anchor once driven, effectively precludes, for economical reasons, any subsequent use of the ground anchor.

The present invention has for an object, the provision of a screw type anchor which may be, with equal facility, threaded or unthreaded into the earth, and so employed repeatedly in different locations.

A further object of the invention is attained in a ground anchor assembly which requires no special tool or wrench for driving, but which may be either driven or removed merely by the application thereto, of any rigid member such as a crowbar or the like.

Yet another object of the invention is attained in an improved anchor assembly including a helical member, a driving point and a combined wrench and rod. Otherwise stated, this object is attained in the provision of a combined guy anchor and driving wrench therefor.

Yet another object of the invention is attained in the provision of a complete anchor assembly, including the means for driving the anchor, of such a nature that the component parts may be assembled without necessitating the usual threaded connections or their equivalents.

Further objects and advantages of the invention will appear as the description proceeds and from the accompanying drawing

forming a part of the present disclosure, and in which:

Fig. 1 is an elevation, partly in section, of an anchor assembly embodying the principles of the present invention; Fig. 2 is a side elevation of a section constituting a half portion of a driving point; Fig. 3 is a side elevation of an identical and companion member to that appearing in Fig. 2, as viewed from an opposite side, and Fig. 4 is a horizontal section along line 4-4 of Fig. 1.

Referring now by characters of reference to the drawing, the device as preferably constructed consists of four parts, respectively designated, generally, as the helix or anchor body 5, an anchor rod 6 and a pair of similarly formed, mating point members 7 and 8. The helical member 5 is preferably formed by casting, say of malleable iron, according to an improved method or process forming the subject matter of a pending application of Thomas B. Bash, bearing Serial No. 302,258, and filed August 27, 1928, as a result of which process the blade is of uniform radial section at all points along the helix between the entering or cutting edge and the trailing edge. The hub portion 9 is formed by preference of a slightly tapered section considered from top to bottom thereof, so as to provide an equal amount of metal about all parts of the driving point assembly, which, as hereinafter appears, extends into a downwardly tapered bore 10 provided in the hub portion. As best appears in Fig. 4, this bore is of a polygonal section for a purpose hereinafter appearing, the internal, polygonal faces being indicated at 11. The point sections 7 and 8 may be and are by preference of identical construction, each forming one-half of the point assembly, the lowermost portions of these members coacting, in the assembly, to form a conical driving point 12. Each of the point members 7 and 8 is by preference provided with a plane peripheral shoulder portion 13 which serves in the assembly to bear against a corresponding plane end face of the hub 9, as best appears in Fig. 1. Extending inwardly or upwardly from the shoulder 13 of each of the point sections 7 and 8, is a tapered plug portion

100

14, characterized by a plurality of tapered external faces 15, the length of the portion 14 and the location and conformity of faces 15, being such as substantially to coincide with 5 the faces 11 within the hub 9, so that the point sections when assembled may be inserted into, and snugly engage the interior polygonal surface of the hub, above described.

As best appears from Figs. 2 and 3, the 10 mating point sections, assuming a pair thereof to be employed, are provided with plane engaging surfaces, this plane of parting between the sections preferably intersecting the median plane or axis of the anchor and anchor rod.

The point sections 7 and 8 are each provided with a half bore 16 (Fig. 2), the upper portion of which may conveniently be 20 of cylindrical conformity and the lower portion of which is, by preference, flared outwardly toward the point 12 for the reception of a similarly flared wrench portion of the anchor rod, hereinafter described. Each 25 of the point sections 7 and 8 is by further preference provided with a recess or pocket 17 (Fig. 2).

The rod 6, above generally referred to, includes by preference, an integrally formed anchor eye 18 which, if desired, may be 30 formed of somewhat heavier section than the shank of the rod 6, and thus serve the dual purpose not only of an eye, but of a thimble, so as to obviate the necessity of a separate thimble in making a connection thereto. 35 Obviously the eye portion may consist of a separate member suitably secured to the shank portion of the rod.

At its opposite end, the rod is preferably deformed, as by drop forging, so as to form 40 thereon a flared driving or wrench portion 19 provided with plane lateral faces 20, the thickness of the upset portion of the rod, between the faces 20, being appreciably less than the dimension transverse thereto. It 45 may here be noted that in the lower portion of the bore 16 in the point sections, there are provided similar plane engaging faces 21, preferably conforming in location and size to the plane faces 20.

50 It will appear that the tapered construction of the polygonal portions of the point sections, coating with the tapered bore of member 8, will serve frictionally to maintain the parts in assembled relation. As an optional, added securing expedient, the hub portion and one of the point sections may be drilled transversely, as shown in Fig. 4, and a pin or key 22, preferably formed of a mild steel or other material relatively softer 55 than the body of the anchor, driven snugly into place to an extent sufficient, preferably, to upset both its inner and outer ends to at least a slight degree. The drilled point section being thus prevented from movement 60 relative to the hub, the other point section,

as well as the rod, are all definitely locked into assembly with the anchor body. It is to be understood, however, that the structure is fully operative without the inclusion of pin 70 22 shown in Fig. 4, and that whether or not the pin 22 is employed, the remaining elements of the structure may be identical in all important respects.

The manner of assembly and use of an anchor constructed as described is thought 75 to be fully apparent from the foregoing description of its parts, but may be briefly set forth for the sake of completeness as follows: The anchor body including the blade 5 and hub 9 is first applied to the rod 6 and brought 80 along the shank portion thereof. The point sections 7 and 8 may then be assembled with their plane mating surfaces in adjacency to each other and about the upset portion 19, in such a manner that the faces 20 lie adjacent to the faces 21, and thus the point sections are 85 effectively prevented from rotation relative to the rod. With the parts thus manually positioned, the hub portion 9 of the anchor body is brought downwardly upon the point sections in exteriorly embracing relation thereto, so that the faces 11 of the hub closely 90 engage the faces 15 of the point sections. Pressure may then be applied to the anchor body in any suitable manner so as to bring the hub portion downwardly about the point sections until the plane lower face of the hub 90 snugly engages the plane shoulder portions 13. Assuming the hub portion 9 and one of the point sections to have been drilled for the 95 reception of pin 22, this element may be inserted and driven home, as above described. It will appear that with the parts in this relation, either with or without employing the pin 22, the helical body of the anchor may 100 be driven by rotary motion applied at any point on the rod 6, and preferably by means of a suitable lever member inserted through the eye 18. By virtue of the tapered construction 105 of the point sections, and the correspondingly tapered bore of the hub 9, it will appear 110 that the parts are so related as to be united more firmly, as tension is applied to the rod 6.

115 As an important incident of the described construction and method of assembly, it will appear that the operative connection between the rod, point sections, and anchor body is in no wise dependent upon a particular direction of rotation of the rod 6 as is the case 120 with the usual threaded connections employing pipe sections or a tubular wrench as a means of driving. A distinct advantage is also offered over the type of anchor requiring a socket engagement between a wrench tube 125 of polygonal section and a corresponding socket in the anchor body, since with such older types of anchor no driving connection between the wrench tube and body can be effected, after the anchor is once set, without excavating about the rod to permit applica- 130

tion of the wrench. According to the present construction no excavation is necessary since the anchor may be manipulated in any case, above the ground level.

5 It will appear that the anchor described is exceedingly simple and economical in construction and provides for certain distinct economies in driving and in use particularly since the utility of the device is not restricted 10 to the particular location in which it happens to be first driven.

While I have described the invention by making specific reference to a presently preferred embodiment thereof, it will appear 15 obvious to those skilled in the art, that a number of changes may be made in the form and arrangement of certain of the parts, as well as in certain details of assembly. The description therefore is to be understood solely 20 in an illustrative, but not in a limiting sense, since obviously a number of changes may be made without departing from the full intentment of the invention, as defined by the appended claims.

25 I claim as my invention:

1. A screw-type earth anchor including a blade, a driving point, a torsion and tension shaft and means carried within the body of the blade and about a portion of the shaft, 30 said means being adapted to prevent relative rotation of the blade and shaft.

2. An earth auger including a blade, a torsion and tension shaft, and a detachable 35 auger point having a sleeve portion of non-circular external periphery for detachably connecting the blade and shaft against relative rotation.

3. In an earth anchor of screw type, an anchor body, a combined torsion and tension 40 member detachably associated therewith, and connecting means for said body and member, adapted to prevent rotational displacement thereof, said means including a sleeve portion arranged for disposition between said body 45 and member.

4. In an earth anchor of screw type, an anchor body, an anchor rod, and means forming 50 a driving point internally engaging the anchor body and externally engaging a portion of the anchor rod, and arranged to position the rod and body relative to each other.

5. In an earth anchor of screw type, a body portion having a helical blade, a combined torsion and tension rod for operative connection with the body portion, and a detachable driving point having means associated therewith constituting a connection between said blade and rod and adapted to prevent relative rotational movement thereof.

60 6. In an earth anchor of screw type, a one-piece body having a helical blade, a central recess in said body, a sectional point assembly 55 extending into said recess and having a central socket therein, and a rod having a deformed portion engaging said socket.

7. In a screw type earth anchor, a body portion, an anchor rod having a driving head near one end, companion members disposed in interlocking relation to said body portion and adapted to receive said driving head, said 70 body portion having an opening therein adapted to receive said companion members and to position said members against rotation relative to the body and relative to the rod.

75 8. In a screw type earth anchor, a body provided with a hub having a bore therein, a rod having an anchor driving portion adapted to extend within said bore and means forming a detachable liner for said bore, embracing in locking relation the driving portion of said rod, and formed for locking engagement within said bore.

80 9. In a screw type anchor, a one piece anchor body having a central aperture therein, a sectional driving point having a portion extending into non-rotational engagement with the apertured portion of the body, said driving point having a recess therein, a combined anchor rod and driving wrench having 85 a deformed head portion extending into and conforming to said recess.

85 10. In a screw type earth anchor, an anchor body having a central hub portion of internal polygonal section, a sectional driving point forming a liner for said hub portion and being of external polygonal section so as to fit within said hub portion in locking engagement therewith, a combined anchor 90 rod and driving member, and means associated with the rod and point for securing the rod and point against relative angular and axial displacement.

95 11. In an earth anchor of screw type, a one-piece anchor body including a helical blade and a hub of internal polygonal section, a pair of companion members forming a driving point normally extending below the anchor body, said companion members being of polygonal external conformity 100 adapted closely internally to engage said hub portion, and having an internally flared bore, an anchor rod having a deformed driving portion adapted to extend within and be closely embraced by the bore in said companion portions.

105 12. In a screw-type earth anchor, an anchor body including a helical blade, a point extending into the anchor body, an anchor rod extending into the body and point, and a member extending through portions of the body and point, for securing the point and rod into assembled relation with the body.

110 13. In a screw type earth anchor, an anchor body including a helical blade and a central hub, a point and a rod extending into opposite ends of the hub, and a pin extending transversely into the hub for securing the rod and point in assembled relation with the body.

14. In a screw type earth anchor, an anchor body including a substantially cylindrical hub portion provided with a central bore of internal polygonal conformity, a pair of companion point members provided with adjacent vertical faces, said point members adapted closely and frictionally to engage the inside surfaces of said hub member and collectively forming a substantially solid conical driving point below the body portion of the anchor, said point sections being recessed over the portion of their length adapted to extend within said hub portion, and a combined anchor rod and driving wrench having a forged driving portion at one end, extending within the recesses of the point members, and provided at its opposite end with an anchor eye.
